UNITED STATES PATENT OFFICE.

SAMUEL T. RICHARDSON, OF CAMBRIDGE, MARYLAND, ASSIGNOR OF ONE-HALF TO J. HOOPER SHEPHERD, OF SAME PLACE.

LEVER-POWER AND DREDGE-WINDER.

SPECIFICATION forming part of Letters Patent No. 236,360, dated January 4, 1881.

Application filed December 3, 1880. (No model.)

To all whom it may concern:

Be it known that I, SAMUEL T. RICHARDSON, of Cambridge, in the county of Dorchester and State of Maryland, have invented a new and Improved Lever-Power Dredge-Winder; and I do hereby declare that the following is a full, clear, and exact description of the same, reference being had to the accompanying drawings, forming part of this specification.

My invention relates to a novel mechanism designed more particularly for winding up oyster-dredges, but applicable also to other analogous uses.

In the business of gathering oysters by the present system of dredging the dredge is hauled along the bottom of the river or bay by a cable attached to the vessel whose movement through the water supplies the power to drag the dredge. Now, this business not only involves the hardest kind of mannal labor in winding up the dredge when full; but is, moreover, attended with very great danger to the man at the windlass, for if, in the progressive movement of the boat, the dredge catches in a rock or other obstruction on the bed of the river, as it frequently does, it is not possible to suddenly check the headway of the boat, and the result is a tremendous back strain on the windlass, jerking the cranks out of the hands of the workmen and whirling them around with such rapidity and violence as to either brain the men outright or permanently cripple the same.

My invention is designed to provide a means for avoiding this danger and at the same time to reduce the manual labor involved, and to this end I abandon the use of cranks, which naturally draw the men into the range of their sweep, and substitute therefor a vibrating lever-power and gears, whose peculiar construction imparts a continuous rotary motion to the windlass-barrel; and in a very compact space serves to utilize the power of the man in a safer and more economical and expeditious manner.

My invention also consists in the peculiar construction and arrangement of devices for quickly disengaging the barrel of the windlass from its shaft when an obstruction is struck, so as to allow the cable to pay out and avoid the backward movement of the gears,

all as hereinafter more fully explained with reference to the drawings, in which—

Figure 1 is a front elevation; Fig. 2, a side elevation; Fig. 3, a rear elevation; Fig. 4, a plan view; and Fig. 5 are details, respectively, of the end of the windlass-barrel and the eccentric tripper.

Referring to these drawings, A represents any suitable frame or pedestal which serves to carry the winding mechanism. This frame must be made with a broad base, so that it may be enabled to resist the strain of the dredge without tearing up the decks, and I preferably make the entire frame of iron.

In forked supports B B is loosely journaled the main shaft C, carrying the windlass-barrel D, upon which the dredge-cable is wound. This barrel is constructed at one end with a clutch, a, which is adapted to fit into another corresponding clutch, a', fixed tightly on the shaft C, so that when these clutches are engaged the shaft and barrel revolve rigidly together, and when disengaged the barrel is capable of an independent rotation on said shaft. On each side of the barrel there is attached to the shaft a ratchet-wheel, E E, permanently and rigidly secured to the shaft; and just inside these ratchet-wheels are corresponding toothed segments F F, which are loosely hung upon the shaft, and whose teeth are beveled and arranged in the curve of a circle. These segments carry on their outer sides dogs G G, arranged in the plane of the ratchet-wheels, and adapted to engage therewith with a pulling movement. At right angles to the plane of the segments F, and fulcrumed upon a support, H, I arrange a vibrating double-headed lever-frame, I, whose heads are curved and provided with beveled teeth, that engage with the teeth of the segments F. This lever-frame is provided on its outside with sockets c, into which are inserted handles J long enough for a proper leverage.

Now, in operating the device as so far described, it will be seen that these handles or levers J are grasped, and being moved up and down simply, it is not necessary that the workmen should throw their bodies into the range of their movement, as with a crank, and besides a greater amount of power is developed from the same exertion. Now, as these

levers are worked, when one is raised—the right one, say—the left one is depressed, and the left-hand bevel-gear will be forced down, and its dog will be dragged down, and the 5 ratchet-wheel on this side will be the working-wheel which turns the shaft and coupled barrel to wind up the windlass. While this is being done it will be seen that the right-hand gear will be rising and its dog will be slipping 10 back over its ratchet-wheel for a new hold. Then, when the movement of the levers is reversed, the gears on opposite sides change functions, and the right one goes to work to continue the winding, while the left takes a 15 new hold, so that by this movement of the levers a continuous rotary movement will be given to the barrel.

I will now describe the tripping mechanism for releasing the barrel from its center shaft. 20 At the end of the barrel next to the clutch (see Fig. 5) is formed a ring-shaped row of ratchet-teeth, *b*, and in the range of these teeth is loosely pivoted a tripper, *s*, which is supported upon a standard or frame-piece, *d*, and 25 which tripper has a series of eccentric teeth designed for engagement with the ratchet-teeth *b* of the barrel. So long as the barrel is turned in the direction necessary to wind up the cable, as shown by the arrow, the tripper 30 *s* rests against the teeth *b*, and the latter pass freely up and under the same. As soon, however, as any backward movement takes place, as from the unusual strain of an obstruction, the ratchet-teeth *b*, in moving back, catch 35 first the short teeth of the tripper, and this throws the tripper down into a horizontal position and causes the most eccentric teeth of the tripper to push the barrel endwise on the shaft and disengage the clutches *a* and *a'*, 40 thus allowing the now loose barrel to turn freely backward on the shaft. In working this part of the device it will be seen that whenever the levers are at rest, as at the end of every up-and-down stroke, the ratchets be- 45 ing then for an instant at rest, the dogs will both drop into the ratchets, and no matter what strain there may be on the barrel there can be no initial back movement to start the tripper, because the toothed lever-frame is 50 held at both ends by both dogs. To permit a slight backward movement then to start the tripper, it is necessary that one of the dogs only should be engaged at this time, and I therefore attach a trip-cord, *e*, to one or the 55 other of the dogs, and as soon as the resistance is felt by the workman in the harder working of the levers, the cord is pulled to lift one of the dogs, and then the back strain coming on one of the dogs it allows the barrel 60 to start backward to the extent of one sweep of the lever-frame, which back movement is utilized to disengage the clutch through the tripper.

In modifying my invention, instead of using simple segments *F F*, I may complete the periphery so as to form them into perfect wheels, and the lever-frame *I*, I may construct with a single complete periphery in the same manner. I may also, if found desirable, cast the clutch *a'* and its adjacent ratchet-wheel together, and allow the segmental gear *F* to turn on a hub of the same.

Now, in defining my invention more clearly, I would state that I am aware that it is not new, as a mechanical movement, to create a continuous rotary movement by an oscillatory movement of levers, and I do not make any claim to having invented this. I am not aware, however, that the same, or any substantially similar mechanism to that shown, has ever before been used; and it has the merit of great strength, economy in applying power, and compactness, the end gears *F F* and the lever-frame *I* serving to house or make a space for the windlass, as clearly shown in Fig. 4.

I am aware, also, that the endwise shifting of the windlass-barrel by an eccentric tripper is not new, and I only claim this when combined with the cord and the working-gear as shown and described.

Having thus described my invention, what I claim as new is—

1. The lever-power dredge-winder herein described, consisting of a rotary winding-axis, a pair of ratchet-wheels rigidly connected thereto, a pair of bevel-gears hung on the winding-axis and having dogs engaging with the ratchet-wheels, and a vibrating lever-frame arranged in a plane at right angles to the bevel-gears, and having teeth engaging therewith, all combined for a continuous movement of the winding-axis, as described.

2. The combination, with a windlass or winding-drum, of a mechanism for converting an oscillatory movement into a continuous rotary movement, arranged as described, to inclose the windlass on three sides.

3. The combination of the winding-shaft *C*, having ratchet-wheels *E E*, the segmental bevel-gears *F F*, carrying dogs *G G*, and the lever-frame *I*, having double-headed bevel-toothed segments, substantially as shown and described.

4. The combination of the winding-shaft *C*, having ratchet-wheels *E* and clutch *a'*, the loose barrel *D*, having clutch *a* and ratchet-teeth *b*, the eccentrically-toothed tripper *s*, mounted upon a fixed support, the bevel-gears *F F*, carrying dogs *G G*, the vibrating lever-frame *I*, having bevel-toothed segments, and the tripping-cord *e*, attached to one of the dogs, substantially as and for the purpose described.

SAMUEL T. RICHARDSON.
